UNITED STATES PATENT OFFICE

ERNEST A. WEEKS, OF KALAMAZOO, MICHIGAN, ASSIGNOR TO ROOT SPRING SCRAPER COMPANY, OF KALAMAZOO, MICHIGAN

ROAD SCRAPER

Application filed December 7, 1928. Serial No. 324,442.

This invention relates to improvements in road scrapers adapted for attachment to trucks although the invention is available in other relations.

5 The objects of the invention are:

First, to provide an electric means for controlling the scraper, lowering it to its work and elevating it to the carrying position.

Second, to provide such an electric means 10 in combination with hydraulic control for the scraper.

Third, to provide such an electric means in connection with a worm gear control for the scraper.

15 Objects pertaining to details and economies will definitely appear from the detailed description to follow. Structures which show preferred embodiments of my invention are illustrated in the accompanying 20 drawing, in which:

Fig. 1 is a plan view of a portion of a truck chassis with my improved adjustable electric control scraper means in position, only so much of the chassis being shown as is necessary to understand my invention.

Fig. 2 is a plan view somewhat reduced in dimension showing the disposition of the electric scraper actuating means and a special auxiliary electric generator in position 30 by the side of the engine for providing the necessary current for operation of the scraper control motor, though the usual starting battery is sufficient for most of the service required.

35 Fig. 3 is an enlarged detail front elevation view of the scraper means as adapted to hydraulic control taken from the left hand of Fig. 1, only a portion of the scraper being shown.

40 Fig. 4 is a detail sectional elevation on line 4-4 of Fig. 3 showing the connections of the hydraulic means for actuating the scraper and a return spring for balancing the weight and facilitating the operation.

45 Fig. 5 is an enlarged detail plan of the hydraulic cylinder and pump, partially in section on line 5-5 of Figs. 3, 4 and 6.

Fig. 6 is an enlarged detail elevation of the pump and hydraulic cylinder connection 50 taken from the right hand of Fig. 5.

Fig. 7 is an enlarged detail sectional elevation on line 7-7 of Figs. 1, 3 and 5, showing the interior and control of the reversible hydraulic pump, the valve being adjusted for operation.

55

Fig. 8 is a similar view to Fig. 7, only partially in section, showing the spring control and connection to the cut off valve.

Fig. 9 is an enlarged detail elevation taken 60 on line 9-9 of Fig. 1 showing the control lever and switch for reversing the motor and controlling the valve.

Fig. 10 is a detail elevation similar to Fig. 3 of a scraper structure showing my invention adapted thereto for a worm drive and 65 control of the scraper.

Fig. 11 is a detail sectional elevation of 70 said worm drive means taken on line 11-11 of Fig. 10.

The parts will be identified by their numbers of reference which are the same in all the views.

1 is the truck chassis. 2 is the truck cab. 3 is the supporting beam or hanger board for the scraper. 4, 4 are the angle bars securing 75 the same to the truck chassis. 5 are curved segments exactly similar at each side of the truck and secured by the hanger boards. 6 and 7 are the clamps for securing the hanger boards 3 adjustably in place. 8 is the scraper 80 rockshaft preferably made of pipe. 9 is the scraper blade. 10, 10 are the C-shaped spring arms for carrying the scraper, this being the form illustrated here although the scraper may be supported in any manner 85 upon the rockshaft. 11 is the centering cable, partially broken away, to maintain the hanger board centrally for adjustment. These parts are like those appearing in my concurrent patent applications.

90

12 is the hydraulic cylinder containing the piston 13 for actuating the rockshaft to control the scraper and rock it to its work and elevate the same for transportation. 14 is a reversible rotary hydraulic pump of the gear 95 type. Other styles of pump are available but not so effective. 15 is the reversible electric motor directly connected to the said reversible pump. 16 is an auxiliary electric generator or other source of electric power for 100

- providing the current for actuating the reversible electric motor. An auxiliary generator merely avoids the extra drain on the starting batteries which are also available.
- 5 The batteries are not shown. 17 is the reverse control switch means located on the floor of the cab. 18 is an independent chain connection to the cut off valve for the hydraulic cylinder.
- 10 The relation of these parts will now be definitely pointed out, it not being purposed to detail the support and adjusting means for the scraper because that is made the subject of independent patent applications in 15 my behalf and is not being claimed here in detail as it is not a part of the invention here disclosed.

The hydraulic cylinder 12 is secured to the hanger board 3 by U-bolt means 121. The 20 piston head 13 is provided with double hydraulic packing for actuation in both directions. The piston rod 131 carries a cross head 132 which is connected by links 133 to rocker arm 81 on the rockshaft 8, so that 25 when the hydraulic cylinder is actuated it acts through the links upon the rockshaft arm and raises or lowers the scraper as the case may be. Return springs 135 are provided to counterbalance the scraper, making 30 it easy in operation either in raising or lowering.

The pump 14 is carried by the cylinder head and is connected by suitable means 140 to the electric motor 15. The pump 14 is 35 provided with intermeshing rotary pump members 141 of the gear type revolving in close fitting bores and being reversible to drive oil, the actuating medium, through the passages 142 to and from the opposite ends of 40 the hydraulic cylinder respectively through the port 143 for the right hand end and through the pipe 144 for the left hand end of the cylinder. A valve 145 is provided to control the passage and shut off the oil directly to the left hand end of the hydraulic cylinder when the pump is stopped, that being the port which it is necessary to positively shut to hold the scraper to its work. The oil is 45 cut off from the opposite end also. The stem 50 of valve 145 projects through stuffing box 146 and is provided with control lever 147 actuated by spring 148 holding the arm against a stop 149 to cut off the said cylinder and maintain the pressure.

55 The electric motor 15 is attached to the hanger board 3 by bolts 150. The electric motor 15 is a reversible motor and is connected by universal joint 140 to drive the pump 14. The motor is controlled by reversing switch 17 placed in the cab and operated by hand lever 171. The said lever 171 is provided with a control arm 172 which connects by cable 173 to the valve arm 147. When the switch lever 171 is at neutral, the 60 valve is closed to the hydraulic cylinder.

When it is moved to either forward or reverse the valve is opened so that the pump can drive the oil from one end of the cylinder 12 to the other and actuate the piston to control the scraper. Automatically the 70 valve is closed when the current is cut off and the pressure is maintained in the left hand end of the hydraulic cylinder.

In Figs. 10 and 11, I show my electric means connected to a worm gear control for the 75 scraper. As pointed out, 18 is a worm gear segment secured to the scraper rockshaft 8. This is operated by worm 19 which is secured by bracket and housing 191 and bolts 192 to the hanger board 3. The bracket 80 housing 191 embraces the worm gear 20 which is carried on the shaft of the worm 19 and the driving worm gear 20 is driven by the worm 21, the shaft of which 211 projects and is connected by the universal joint 151 to driving 85 shaft of the reversible motor 15. The control connections to this motor are the same as the connections to the motor for the hydraulic cylinder except the connecting arm 172 is unnecessary to control the cut off valve to the 90 cylinder.

It will be seen that by controlling the motor and driving the same ahead, or reversing that, the scraper can be effectively controlled, and as the worm gear locks the scraper is effectively controlled as required. 95

The end of the shaft 211 projects at 212 and affords means for connecting a crank to manipulate this structure by hand in the event of the failure of the electric current 100 supply or motor.

A hand pump can, of course, be provided for controlling the hydraulic means in the event of the failure of the motor. I have not deemed it necessary to illustrate such as it 105 is not necessarily a part of my invention.

Having thus described my invention, I desire to state that it is capable of great variations so far as the application of the electric power for manipulation of the scraper is concerned. I show both the hydraulic and the worm gear means mounted on the hanger board for controlling the scraper. There are advantages for the hydraulic and there are advantages for the worm gear. I wish to 110 claim the same specifically in the forms illustrated and carried by the hanger board as well as broadly as pointed out in the appended claims.

Having thus described my invention, what 115 I claim as new and desire to secure by Letters Patent, is:

1. The combination with a truck chassis of adjustable scraper hanger board thereon, a scraper rockshaft with scraper attached, carried by the said hanger board, a hydraulic cylinder carried by the hanger board with connections for controlling the scraper to elevate and lower the same, a reversible electric motor with hydraulic pump for controlling 120 125 130

5 said hydraulic cylinder disposed on the hanger board, and switch means in the cab to control the electric motor with connection for cutting off the hydraulic cylinder, as specified.

10 2. In an actuating means for road scrapers, the combination of a rockshaft, a scraper carried thereby, a hydraulic cylinder with double acting piston, connections from the said piston for operating the said rockshaft, a reversible geared power pump connected to and associated with the said cylinder, a reversible electric motor connected with said power pump, a switch means in the cab for controlling the said motor, a shut off valve for the said hydraulic cylinder and a connection to the switch for actuating said valve to cut off the cylinder when the motor is stopped, as specified.

15 20 3. The combination of a motor truck, a hanger board therefor, a scraper on a rockshaft carried by the hanger board, an electric motor supported on the said hanger board, and power connections from the motor for operating the said scraper, as specified.

25 20 4. In an actuating means for road scrapers, the combination of a rockshaft, a scraper carried thereby, a hydraulic cylinder with double acting piston, connections from the said piston for operating the said rockshaft, a geared power pump connected to and associated with the said cylinder, an electric motor connected with said power pump, a switch means in the cab for controlling the 30 35 said motor, a shut off means for the said hydraulic cylinder to cut off the cylinder when the motor is stopped, as specified.

In witness whereof I have hereunto set my hand.
